SLIP MECHANISM

Application filed March 28, 1932. Serial No. 601,561.

This invention relates to slip mechanisms for locking various devices in a well casing, and particularly to a slip mechanism for use with a well cleaner.

5 A broad object of the invention is to prevent premature setting of slips in a slip mechanism while the latter is being run into the casing.

Another object is to increase the reliability 10 and simplify the construction of a slip mechanism.

In my copending application, Serial No. 550,682, filed July 14, 1931, on oil well cleaning device there is disclosed a well cleaner 15 incorporating a slip mechanism comprising a slip expander mounted upon a hollow sleeve; slips positioned about the expander; an upper collar slidably upon the sleeve below the expander, to which collar the slips are mechanically linked; a lower collar also slidably positioned upon the sleeve below the upper collar and joined thereto by a plurality of springs which are outwardly bowed at 20 their centers to frictionally engage a well casing. A locking mechanism is provided for maintaining the lower collar near the lower end of the sleeve to retract the slips to the lower end of the slip expander, (in which position the slips are contracted) while the 25 mechanism is being lowered into the casing.

The structure described functions very satisfactorily in straight uniform casing but if there is a bend or constriction in the casing one or more of the outwardly bowed casing 30 engaging springs may be forced inwardly by the casing, thus straightening it and lengthening it and forcing the upper collar and slips upwardly. As a result of this upward movement the slips may be expanded sufficiently to cause one or more of them to engage the casing, and thus lock the device to the casing.

In accordance with the present invention 45 the aforementioned objectionable characteristic of a slip mechanism constructed as described is eliminated by locking the upper collar instead of the lower collar to the sleeve, thus rigidly anchoring the slips in their lowest position on the slip expander inde-

pendently of the bowed casing-engaging springs.

The invention will now be described in detail with reference to the drawing, in which

Figure 1 is an elevational view of the slip 55 mechanism in a well casing with the slips retracted;

Figure 2 is an elevational sectional view of the device;

Figure 3 is a detail, sectional view showing 60 the device with the slips expanded; and

Figure 4 is a developed view showing the complete surface outline of the upper collar and slot therein.

Referring to the drawing, my device comprises a central shaft 1 upon which there is slidably mounted a sleeve 4, upon which is rigidly mounted a slip expander 2, a slip link collar 3. The upper end of shaft 1 is threaded into a coupling union 5 which in turn may 70 be threaded to any tool which it is desired to use in connection with the slip mechanism, it being understood that the tool in turn is connected to a string of tubing extending to the top of a well. A feeler head 6 is mounted 75 upon the lower end of the central shaft 1.

The slip expander 2 comprises a member bored to receive the shaft 1 and provided with slip seats 7 on its outer face. Four slip seats have been shown in the drawing, but any desired number may be used. Each slip seat extends upwardly and outwardly and carries a slip 8 which is slidable in the seat 7 from a lower position as shown in Figures 1 and 2 in which the slips are retracted out of engagement with the casing, to an upper position as shown in Figure 3 in which they are wedged into contact with the casing. Each slip is provided with teeth as shown, to better engage the casing.

Each slip 8 is pivotally secured by a pin 9 to a link 10 which extends downwardly below the slip and is pivotally connected to a collar 3 slidably mounted upon the sleeve 4. It will be observed that with this arrangement, downward movement of the expander head 2 with respect to the collar 3 will force all the slips 8 upwardly along the slip seats 7 and into engagement with the casing.

Rotatably secured to the slip link collar 3 is 100

a locking collar 11 which is provided with an annular groove 12 engaging with an annular ridge 13 on the link collar 3 so that the two collars are secured against relative vertical movement but are free to rotate independently of each other. The locking collar 11 is provided with a spiral slot 14 having a depression 15 at its upper end, and opening into the lower edge of the collar 11 at its lower end 10 as clearly shown in Figure 4. A pin 16 extends radially from the wall of sleeve 4 and is engageable with the slot 14 by rotating the sleeve relative to the collar 11. When the pin 16 is positioned in the end 15 of slot 14 it 15 serves to retain the collar 11 in its lower position, in which the slips 8 are retracted.

It is necessary to maintain the slips in retracted position as shown in Figure 1 while the device is being run into a casing and to 20 prevent the pin 16 from being moved out of the slot 14 by jolting or unintentional rotation of the slips, a collar 17 is rigidly secured to the sleeve 4 a short distance below the pin 16 and a spiral spring 18, together with a 25 washer 19, positioned about the sleeve 4 between the collar 17 and the pin 16. With this construction it will be observed from an inspection of Figure 1 that when the pin 16 is positioned in the depressed end 15 of the 30 slot 14 the spring 18 is compressed between the upper edge of fixed collar 17 and the lower edge of the locking collar 11. As a result, the spring maintains a pressure between the pin 16 projecting from sleeve 4 and the 35 notched end 15 of slot 14, thus preventing the pin from being accidentally dislodged from the end of the slot.

Slidably mounted upon the sleeve 4 is another collar 20 which is connected to the locking collar 11 by a plurality of bowed spring members 21 which are provided to frictionally engage with the well casing at all times to provide a desired amount of friction between the upper collar 11 and the casing.

45 The lower end of sleeve 4 is provided with a head 22 which is rigidly attached to the sleeve. The lower edge of this head 22 is half cut away to provide shoulders 23 engageable with similar juxtaposed shoulders 24 on the head 6, which is rigidly attached to the lower end of the central tubular member 1. The purpose of these shoulders will be made clear from a description of the operation of the device.

50 Assume that the coupling 5 at the upper end of tube 1 is secured to a well cleaner or some other tool that is to be lowered into a well, and that the upper end of the packer in turn is secured to a string of tubing and 55 that the entire assembly comprising the slip mechanism and the well cleaner or other tool has been lowered into a casing to a point where it is desired to lock the assembly to the casing. Previous to the insertion of the slip mechanism into the casing the pin 16 would

be turned into the slot 14 and locked in the end 15 thereof by the spring 18 bearing between collar 17 fixed to the sleeve 4 and the lower edge of the lock collar 17. This retains the slips in their lowermost position 70 with respect to the expander head 2 so that the slips are retained in retracted position as shown. It will be observed that should the device pass through bent or distorted casing while being lowered into the well, any inward displacement of the bowed spring members 21 will merely result in forcing the lower collar 20 down along sleeve 4, since the upper lock collar 17 is securely retained 75 against upward movement by the pin 16.

It should be further noted that while the device is being lowered into the well the friction between the bowed springs 21 and the casing constitutes sufficient drag to maintain the head 2 and the sleeve 4 on the upper end 80 of the shaft 1 so that the expander 2 abuts against the lower end of the coupling member 5.

When the proper position in the casing has 85 been reached and it is desired to set the slip mechanism, the tubing string is elevated, a short distance, thus sliding shaft 1 upwardly through the sleeve 4 until the head 6 on the end of shaft 1 abuts against the head 22 on the lower end of sleeve 4. The tubing string 90 is then rotated to the right while at the same time it is being maintained in a slight upward movement until the head 6 is so positioned as to engage the faces 24 with the faces 23 on head 22. Thereafter, continued rotation to the right of the string of tubing and 95 shaft 1 will rotate sleeve 4 and the pin 16 projecting therefrom; collar 11 however, is restrained from rotation since it is secured to the upper ends of the bowed spring members 21 which are in frictional engagement with the casing. Therefore the pin 16 will 100 be rotated out of engagement with slot 14.

After the tubing string has been rotated 105 to the right sufficiently to release pin 16 from engagement with slot 14 as described, the rotation is stopped and the string of tubing is again lowered in the casing until the coupling 5 strikes the top of the expander head 2 and forces it, together with the sleeve 4, 110 downward within the well casing. Since the lock collar 11 is slidably mounted upon the sleeve 4 and is frictionally engaged to the casing through the bowed springs 21, it will 115 tend to remain stationary in the casing and will tend to maintain the slips 8 stationary 120 since they are attached to collar 11 by the links 10 and collar 3. The expander head 2 will therefore be forced downward with respect to the slips 8, which will ride up on 125 their seats 7 until they touch the casing and lock therewith. The locking of the slips with the casing securely anchors the entire assembly to the casing.

When it is desired to withdraw the assem- 130

bly, the slips are released by lifting the string of tubing and the shaft 1 until the head 6 on the lower end of shaft 1 strikes the head 22 on the lower end of sleeve 4; thereafter 5 further elevation of the shaft 1 elevates the sleeve 4 and the expander head 2 and the slips, which are frictionally engaged with the casing, slide downward along their seats 7 until they are disengaged from the casing. 10 The elevation of sleeve 4 will be continued until the pin 16 strikes the lower end of collar 11. The string of tubing and shaft 1 will then be rotated to the left, while still being elevated, until the faces 24 on head 6 15 engage with faces 23 on the head 22 and rotate the sleeve 4. Since rotation of the collar 11 is resisted by the frictional engagement of the bowed springs 21 with the casing, pin 16 projecting from sleeve 4 will be rotated 20 with respect to collar 11 and will engage with the slot 14 as shown in Figure 1. Thereafter, the entire assembly may be withdrawn entirely from the casing or, if desired, it may be raised to a higher level and again locked 25 to the casing by repeating the operations already described.

The construction whereby the pin 16 on sleeve 4 is engaged with a slot in the upper collar 11 instead of the lower collar 20, in 30 addition to preventing any possibility of the slip being prematurely set while the device is being lowered through bent or distorted casing, permits the positioning of the collar 17 and spring 18, within the casing engaging 35 springs 21 above the collar 20 instead of below the collar 20. This is advantageous as it permits shortening of the sleeve 4.

I claim:

1. A slip mechanism comprising a sleeve, 40 a slip expander mounted on said sleeve having slip seats thereon extending upwardly and outwardly, said sleeve extending below said expander, slips mounted on said slip seats, an upper collar slidably mounted on said sleeve 45 below said expander, means connecting each slip to said upper collar, a lower collar slidably mounted on said sleeve and spaced below said upper collar, a plurality of outwardly bowed casing-engaging springs having their 50 upper and lower ends secured to said upper and lower collars respectively, said upper collar being movable on said sleeve from an uppermost position in which said slips are in set position to a lowermost position in which said 55 slips are in contracted position, a slot in said upper collar opening from the bottom edge thereof and extending upwardly and then downwardly, a pin projecting from said sleeve and engageable with said slot by relative rotation between said upper collar and said sleeve to lock said upper collar into its 60 lowermost position, a third collar rigidly connected to said sleeve between said upper and lower collars, a spiral spring surrounding 65 said shaft between said pin and said third

collar, said spring being compressed between said upper and third collar when said pin is rotated into engagement with said slot, and means for rotating said sleeve.

2. In a device for insertion into a well casing and adapted to be locked to the casing at will, a shaft adapted to be lowered into and turned within a well casing, a sleeve slidable on said shaft, a slip expander mounted upon said sleeve, slips longitudinally slidably mounted in slip seats on said expander, said slip seats being inclined upwardly and outwardly whereby upward movement of said slips relative to said expander expands the slips against the casing, a collar slidably mounted upon said sleeve and linked to said slips, said collar having a slot therein opening from the lower edge thereof, said slot terminating in a downwardly extending closed end portion, spring means for frictionally engaging said collar to the well casing, a pin extending from said sleeve engageable with the slot in said collar by rotation of said sleeve with respect to said collar, a second collar fixed to said sleeve below said pin and a spiral spring surrounding said sleeve and positioned above said second collar, said spring being compressed between said two collars when said pin is in the downwardly extending closed end portion of said slot.

Signed at Los Angeles, California, this 19th day of March, 1932.
